Schaeffer

[11] Patent Number: Des. 377,337

[45] Date of Patent: **Jan. 14, 1997

[54] **ACTUATOR FOR A PUSHBUTTON
ELECTRICAL SWITCH**

[75] Inventor: Maurice Schaeffer, Strasbourg, France

[73] Assignee: **Baco Constructions Electriques -
Anct. Baumgarten S.A.**, France

[**] Term: 14 Years

[21] Appl. No.: 820,047

[22] Filed: Jan. 13, 1992

[52] U.S. Cl. D13/171

[58] Field of Search D13/158, 171,
D13/174; 200/293, 296, 302.1, 336, 341,
412, 417, 520

[57] **CLAIM**

The ornamental design for an actuator for a pushbutton electrical switch, as shown and described.

DESCRIPTION

FIG. 1 is a perspective view of an actuator for a pushbutton electrical switch showing my new design;

FIG. 2 is a front elevational view of FIG. 1;

FIG. 3 is a side elevational view of FIG. 2;

FIG. 4 is a top plan view of FIG. 1; and,

FIG. 5 is a bottom plan view of FIG. 1.

The side opposite to FIG. 2 is identical to FIG. 2 and the side opposite from FIG. 3 is identical to FIG. 3.
